Primary Examiner — Daniel Bui*Assistant Examiner* — Andrew Kerr*(74) Attorney, Agent, or Firm* — Wood Herron & Evans LLP(57) **CLAIM**

The ornamental design for a rear tailgate, as shown and described.

DESCRIPTION

FIG. 1 is a right rear perspective view of the rear tailgate, showing my invention;

FIG. 2 is a left front perspective view of the rear tailgate for a vehicle shown in FIG. 1.

FIG. 3 is a front view thereof.

FIG. 4 is a rear view thereof.

FIG. 5 is a right side view thereof.

FIG. 6 is a left side view thereof.

FIG. 7 is a top view thereof; and,

FIG. 8 is a right rear perspective view thereof in use condition.

The broken line surrounding the dark image represents the boundary of the claimed design and the de-emphasized or half-toned portion represents unclaimed environment and forms no part of the claimed design.
